UNITED STATES PATENT OFFICE

121,074

DESIGN FOR AN IRONING MACHINE

Thomas James Little, Jr., Syracuse, N. Y., assignor to Easy Washing Machine Corporation, Syracuse, N. Y., a corporation of Delaware

Application March 25, 1940, Serial No. 91,235

Term of patent 7 years

To all whom it may concern:

Be it known that I, Thomas J. Little, Jr., a citizen of the United States of America, residing in the city of Syracuse, county of Onondaga, and State of New York, have invented a new, original, and ornamental design for an Ironing Machine, of which the following is a specification, reference being had to the accompanying drawings, forming part thereof.

Figure 1 is a top plan view of an ironing machine, showing my new design;

Figure 2 is a front view thereof;

Figure 3 is a view of the right end of the ironing machine as shown in Figure 2;

Figure 4 is a rear elevation of the ironing machine; and

Figure 5 is a left end view of the ironing machine as referred to in Figure 2.

I claim:

The ornamental design for an ironing machine, substantially as shown.

THOMAS JAMES LITTLE, JR.
